GAME TO TEST DEXTERITY

James O. Kuhn, Cincinnati, Ohio, assignor to Bromo Mint Company, Cincinnati, Ohio, a corporation of Ohio

Application September 4, 1958, Serial No. 52,500

Term of patent 7 years

(Cl. D34—5)

Fig. 1

Fig. 2

Fig. 3

Fig. 4

Figure 1 is a top plan view of a game to test dexterity showing my new design.

Figure 2 is a fragmentary front elevational view thereof.

Figure 3 is an end elevational view thereof.

Figure 4 is a cross sectional view taken on the line 4—4 of Figure 1.

The dominant feature of my design resides in the portion shown in full lines.

I claim:

The ornamental design for a game to test dexterity, substantially as shown and described.
